PYROLYTIC DECOMPOSITION OF HYDROCARBONS

Filed Feb. 27, 1928

Inventor:
Frank K. Ovitz,
By Dyanforth, Clutton & Kiley,
Atty's.

UNITED STATES PATENT OFFICE

FRANK K. OVITZ, OF WHITING, INDIANA, ASSIGNOR TO STANDARD OIL COMPANY, OF WHITING, INDIANA, A CORPORATION OF INDIANA

PYROLYTIC DECOMPOSITION OF HYDROCARBONS

Application filed February 27, 1928. Serial No. 257,524.

This invention relates to pyrolytic decomposition of hydrocarbons and particularly to the prevention of corrosion of the metallic apparatus employed for such decomposition.

5 The invention will readily be understood from the following description in connection with the accompanying drawing which shows diagrammatically an apparatus whereby hydrocarbon oils may be pyrolytically decomposed and the resulting products recovered.

Referring to the drawing, 10 is a heating coil; 11 is a retort or conversion chamber; 12 is the reflux condenser for overhead from said chamber; 13 is a flash drum for tar from chamber 11; 14 is a filter for the residue from said flash drum; 15 is a fractionating condenser for the overhead from the flash drum; 16 is a receiver for the heavy condensate therefrom; 17 is a tank in which a portion of said condensate is adapted to be charged with hydrated iron oxide; and 18 is a feed pipe leading to the heating coil 10.

A pump 19 is provided for supplying charging stock under pressure to the heating coil 10. The outlet 20 of the heating coil 10 leads into the conversion chamber 11, which is maintained at a desired cracking temperature by burners 21. The conversion chamber 11 is suitably provided with a

scraper 40 for the purpose of removing coke forming material from the walls thereof and causing it to fall to the bottom of the chamber. From the upper end of the conversion chamber 11 a vapor pipe 22 leads to the reflux condenser 12, which may be provided with suitable fractionating and condensing devices (not shown). A vapor pipe 42 leads from the top of the fractionating condenser 12 to a suitable condenser (not shown). Re-

flux condensate may be returned from the condenser 12 through line 23 by pump 28 to the heating coil 10. From the lower end of the conversion chamber 11 a pipe 24 leads to the flash drum 13, said pipe 24 being pro-

vided with a valve 25. From the top of the drum 13 a pipe 26 leads to the lower part of the fractionating condenser 15 which is provided with suitable fractionating and condensing devices (not shown). From the base of this condenser a pipe 27 leads into

the receiver 16 and from the top thereof a pipe 43 leads to a suitable condenser (not shown). From the underside of the drum 13 a pipe 28 leads into the filter 14. A suitable pump, for example, at hot oil pump 29 is provided in the line 28 for forcing the pressure tar residuum into the filter 14.

55 The filtered pressure tar residuum passes from the filter 14 by pipe 30.

The heavy pressure tar distillate receiver 60 16 is provided with a valved outlet 31 and an outlet 32 which leads into the bottom of the tank 17. A pump 33 is provided in the line 32.

65 The tank 17 is provided with a perforated pipe 34 which is adapted to inject air into the contents thereof. From a low position on the tank 17, a pipe 35 leads to the upper portion of said tank. Said pipe 35 is provided with a circulating pump 36 and a hopper 37 by means of which hydrated iron oxide and other substances such as water, may be added to the oil circulated by the pump 36 and may thereby be disseminated 70 throughout the oil in tank 17. From the bottom of tank 17, a pipe 38 leads into the feed line 18. A pump 39 is provided in the line 38.

75 The operation is as follows:

Heavy pressure tar distillate is pumped 80 from receiver 16 through line 32 by pump 33 into tank 17 until it is nearly full. The distillate is then circulated through the 85 by pump 36 from the bottom to the top of the tank 17. Hydrated iron oxide in finely 85 divided form is fed into the circulating oil by the hopper 37 and is carried by the circulating oil by the hopper 37 and is carried by the circulating oil into tank 17. A certain 90 amount of water may then be supplied by hopper 37, if desired, said water assisting somewhat in the production of a satisfactory suspension of the iron oxide in the oil. While the suspension is being produced and, 95 also preferably while it is being used, the oil in the tank 17 is agitated by air introduced by the perforated pipe 34. It is preferred to produce in this manner a suspension of iron oxide containing approximately 1.5 lbs. per 100

gallon. The amount of water used may suitably be about 0.8% by volume of the oil.

The charging stock which is supplied to the heating coil 10 through line 18 by the 5 pump 19 may be any suitable hydrocarbon oil heavier than gasoline, such as gas oil, paraffin light ends, pressure tar distillate, heavy paraffin distillate, or mixtures of two or more thereof. The oil containing sus- 10 pended hydrated iron oxide is fed to the charging stock through line 38 by the pump 39 in quantity sufficient to provide a suitable oxide content in the oil passing through the heating coil 10 and conversion chamber 11. 15 A suitable quantity of oxide is approximately 0.5 lbs. per barrel of charging stock i. e. about 0.17% by weight. It must be understood that this amount will vary with stocks of different character and origin, but 20 the proportion of such oxide ordinarily will not exceed a fraction of 1% relative to the weight of the oil.

The temperature and pressure conditions in the heating coil 10 and the conversion 25 chamber 11 may vary within wide limits. For example, the outlet temperature of the heating coil 10 may suitably be about 820 to 850° F. and the pressure may suitably be about 325 to 400 lbs. per square inch. The 30 chamber 11 may be heated by the burners 21 to maintain a suitable cracking temperature therein.

The fractionating condenser 12 is controlled to give a pressure distillate of the 35 desired character, the vapors of which pass off by pipe 42 and are condensed. The reflux from condenser 12 is returned to the heating coil 10 through pipe 23 by pump 23a.

Pressure tar is drawn off from the bottom 40 of chamber 11 and is accompanied by more or less coke which is produced in the oil, as well as iron oxide and iron sulfide which are disseminated in solid form in the coke and in the tar. The withdrawal is effected con- 45 tinuously, or periodically, through the valve 25 and pipe 24 and the tar is flashed in the drum 13 which is maintained substantially at atmospheric pressure. The overhead passes by a pipe 26 to the fractionating con- 50 denser 15 in which the heavy pressure tar distillate is condensed, the condensate passing by pipe 24 to the receiver 16. The light pres- 55 sure tar distillate vapors pass by pipe 43 to a suitable condenser (not shown).

Ordinarily, only a small part of the heavy 60 pressure tar distillate is used in the tank 17 for the production of the suspension of iron oxide in oil; the remainder is withdrawn by pipe 31 to be used in producing blended charged stock.

The pressure tar residue is pumped in a hot 65 condition through pipe 28 by pump 29 into the filter 14. Ordinarily it is preferred to use a pressure filter, but any other filter may be used. Among others, filters of the Sweet-

land and Kelly type are suitable. The filter surfaces may suitably be constituted by woven metal, such as fabrics woven from steel, copper, brass or other suitable metallic wire.

The hydrated iron oxide combines with the sulfur and sulfur-compounds which exert a corrosive effect upon the metal of the apparatus so that internal corrosion from this cause is substantially prevented. The proportion of hydrated iron oxide is so small that the fluidity of the oil undergoing treatment is not substantially impaired. Further, the hydrated iron oxide and iron sulfide produced therefrom, together with the coke, constitute a suitable filter medium which materially aids in preventing passage of other solid material while permitting the liquid constituent of the tar to pass through the filter.

While I prefer to employ hydrated iron oxide, it must be understood that iron oxides and other oxygenated compounds such as carbonates, which will react with sulfur and sulfur compounds under the conditions of the 80 operation, may be employed in finely divided form according to the invention.

Although the present invention has been described in connection with the details of a specific embodiment thereof, it is not intended that such details should be regarded as limitations on the scope of the invention except in so far as included in the accompanying claims.

I claim:

1. In the art of converting higher boiling hydrocarbon oils into lower boiling hydrocarbon oils wherein such oil is subjected to cracking conditions of temperature and pressure while confined within metallic apparatus, the method of reducing corrosion of said metallic apparatus by the said oil undergoing cracking which comprises maintaining in the presence of said oil undergoing conversion, hydrated iron oxide in the amount of not more than a fraction of 1%.

2. In the art of converting higher boiling hydrocarbon oil wherein such oil is subjected to cracking conditions of temperature while flowing through a confined metallic passageway and is passed therefrom while at a cracking temperature to an enlarged metallic chamber wherein it undergoes further cracking, the method of retarding corrosion of said metallic passageway and said metallic chamber by the said oil undergoing cracking, which comprises admixing with the oil, prior to its introduction into said metallic passageway, not more than a fraction of 1% of hydrated iron oxide.

3. In the art of converting higher boiling hydrocarbon oils into lower boiling hydrocarbon oils wherein such oil is subjected to cracking conditions of temperature and pressure while confined within metallic apparatus,

the method of reducing corrosion of said metallic apparatus by the said oil undergoing cracking which comprises maintaining in the presence of said oil, undergoing conversion, an amount of not more than a fraction of 1% of hydrated iron oxide substantially free of absorbed alkali.

4. In the art of converting higher boiling hydrocarbon oils into lower boiling hydrocarbon oils wherein such oil is subjected to cracking conditions of temperature while flowing through a confined metallic passageway, said oil being passed from said passageway while at cracking temperature to an enlarged metallic chamber wherein it undergoes further cracking, the vaporous products of conversion and the heavy liquid residual products of conversion being separately withdrawn from said chamber and the latter products being passed through a filter element, the method of retarding corrosion of said metallic passageway and chamber by the said oil undergoing cracking, which comprises admixing with the oil, prior to its introduction into said passageway, not more than a fraction of 1% of hydrated iron oxide.

5. The method of decomposing hydrocarbon oils which comprises cracking the oil under pressure, withdrawing unvaporized liquid products and passing them to a zone of lower pressure wherein light and heavy fractions are formed, mixing iron oxide with said light fractions, and returning said mixture to the oil being cracked.

33. In witness whereof I have unto set my hand this 9th day of February, 1928.
